UNITED STATES PATENT OFFICE

171,280

COMBINED CAN AND CLOSURE CAP THEREFOR

Leonard E. Juengling, Kansas City, Kans., assignor to Cook Chemical Company, Kansas City, Mo.

Application May 5, 1952, Serial No. 19,591

Term of patent 3½ years

(Cl. D58—26)

To all whom it may concern:

Be it known that I, Leonard E. Juengling, a citizen of the United States, residing at Kansas City, in the county of Johnson and State of Kansas, have invented a new, original, and ornamental Design for a Combined Can and Closure Cap Therefor, of which the following is a specification, reference being had to the accompanying drawing, forming a part thereof.

Fig. 1 is a perspective view of a combined can and closure cap therefor, showing my new design;

Fig. 2 is a side elevational view thereof;

Fig. 3 is an inverted plan view thereof; and

Fig. 4 is a cross-sectional view thereof taken on line IV—IV of Fig. 2.

The dominant features of the design reside in the portions shown in full lines.

I claim:

The ornamental design for a combined can and closure cap therefor, as shown and described.

LEONARD E. JUENGLING.
